(57) **CLAIM**
The ornamental design for a fluorometer, as shown and described.

DESCRIPTION

FIG. 1 is a front perspective view of a first embodiment of a fluorometer of our new design.

FIG. 2 is a front view of the fluorometer of FIG. 1.

FIG. 3 is a back view of the fluorometer of FIG. 1.

FIG. 4 is a right side view of the fluorometer of FIG. 1.

FIG. 5 is a left side view of the fluorometer of FIG. 1.

FIG. 6 is a top view of the fluorometer of FIG. 1.

FIG. 7 is a bottom view of the fluorometer of FIG. 1.

FIG. 8 is a front perspective view of a second embodiment of a fluorometer of our new design.

FIG. 9 is a front view of the fluorometer of FIG. 8.

FIG. 10 is a back view of the fluorometer of FIG. 8.

FIG. 11 is a right side view of the fluorometer of FIG. 8.

FIG. 12 is a left side view of the fluorometer of FIG. 8.

FIG. 13 is a top view of the fluorometer of FIG. 8.

FIG. 14 is a bottom view of the fluorometer of FIG. 8.

FIG. 15 is a front perspective view of a third embodiment of a fluorometer of our new design.

FIG. 16 is a front view of the fluorometer of FIG. 15.

FIG. 17 is a back view of the fluorometer of FIG. 15.

FIG. 18 is a right side view of the fluorometer of FIG. 15.

FIG. 19 is a left side view of the fluorometer of FIG. 15.

FIG. 20 is a top view of the fluorometer of FIG. 15.

FIG. 21 is a bottom view of the fluorometer of FIG. 15.

FIG. 22 is a front perspective view of a fourth embodiment of a fluorometer of our new design.

FIG. 23 is a front view of the fluorometer of FIG. 22.

FIG. 24 is a back view of the fluorometer of FIG. 22.

FIG. 25 is a right side view of the fluorometer of FIG. 22.

FIG. 26 is a left side view of the fluorometer of FIG. 22.

FIG. 27 is a top view of the fluorometer of FIG. 22; and,

FIG. 28 is a bottom view of the fluorometer of FIG. 22.

The bottom view of our design and the portions depicted in broken lines are not part of the claimed design.
